US00D537702S

(12) **United States Design Patent** (10) Patent No.: **US D537,702 S**
Roberts, III (45) Date of Patent: **** Mar. 6, 2007**

(54) **DOOR LEVER**(75) Inventor: **Rockwood Theodore Roberts, III**,
Indianapolis, IN (US)(73) Assignee: **Schlage Lock Company**, Indianapolis,
IN (US)(**) Term: **14 Years**(21) Appl. No.: **29/243,449**(22) Filed: **Nov. 23, 2005**(51) LOC (8) Cl. .... **08-06**(52) U.S. Cl. .... **D8/308**(58) Field of Classification Search D8/300,
D8/301, 302, 308, 309, DIG. 10, 338; D23/250,
D23/251, 252, 254, 241–242, 238–239; 4/675–678;
292/336.3; 74/557; 70/91, 101; 16/110.1

See application file for complete search history.

Primary Examiner—Paula A. Greene

(74) Attorney, Agent, or Firm—Michael Best & Friedrich
LLP(57) **CLAIM**The ornamental design for a door lever, as shown and
described.**DESCRIPTION**FIG. 1 is a perspective view of a door lever showing the new
design for a door lever;

FIG. 2 is a left side elevation view of FIG. 1;

FIG. 3 is a front elevation view of FIG. 1;

FIG. 4 is a top elevation view of FIG. 1;

FIG. 5 is a rear elevation view of FIG. 1; and,

FIG. 6 is a bottom elevation view of FIG. 1.

The broken-line disclosure in the views is for illustrative
purposes only and forms no part of the claimed design.**1 Claim, 1 Drawing Sheet**## U.S. PATENT DOCUMENTS
